Specification for Design.

Patented Feb. 28, 1922.

Application filed August 25, 1921. Serial No. 495,402. Term of patent 7 years.

To all whom it may concern:

Be it known that I, VICTOR GAERTNER, a citizen of the United States, residing at New York city, in the county and State of New York, have invented a new, original, and ornamental Design for a Bread Tray or Similar Article, of which the following is a specification, reference being had to the accompanying drawings, forming a part thereof, and in which—

Fig. 1 is a top view,
Fig. 2 a longitudinal section on the line

2—2 of Fig. 1, and

Fig. 3 a transverse section on the line
3—3 of Fig. 1, of a bread tray embodying my design.

I claim:

The ornamental design for a bread tray or similar article, as shown.

VICTOR GAERTNER.
